MACHINE FOR AND METHOD OF FOLDING SHEETS

John Perry, Pearl River, N. Y., assignor to Dexter Folder Company, New York, N. Y., a corporation of New York

Application February 19, 1931. Serial No. 517,051

28 Claims. (Cl. 270—81)

This invention relates to folding machines, and while capable of general use, is more particularly adapted for use on folding machines wherein the sheet receives a plurality of folds 5 in the course of making it into a multi-fold product.

One object of this invention is to provide an improved folding machine which eliminates wrinkling of the sheet that has sometimes resulted heretofore from the folding operation.

Another object of this invention is to provide an improved folding machine which facilitates the folding of heavy stock without wrinkling and without danger of choking up the folding devices.

Another object of this invention is to provide an improved folding machine which enables the folding devices to operate on the proper line of fold of the sheet, regardless of the size and 20 thickness of said sheet.

Another object of this invention is to provide an improved folding machine which properly registers the fold line of the sheet with the folding devices, after the fold line has been 25 weakened at one side of the devices to facilitate folding of the sheet thereby.

Another object of this invention is to provide a folding machine with improved means for registering the fold line of the sheet with 30 the folding devices.

Another object of this invention is to provide a folding machine with improved means for perforating or weakening the sheet on the fold line to facilitate folding of the sheet and 35 eliminate wrinkling of the same.

Another object of this invention is to provide a folding machine with improved means which perforates or weakens the sheet on the fold line and has a shearing action that reduces the 40 strain on said means and enables the same to operate accurately regardless of the size or thickness of the sheet.

Another object of this invention is to provide a folding machine with improved sheet perforating means and novel clamping means associated therewith and acting to clamp or hold the sheet 45 against displacement while being perforated or weakened on its fold line.

Another object of this invention is to provide 50 a folding machine with improved means acting to perforate or weaken the sheet on its fold line while said line is at one side of the folding means and before the sheet is in position to register the fold line with the folding devices.

Another object of this invention is to provide 55 a folding machine with improved sheet clamping, perforating, stripping, and registering devices associated and constructed in a novel manner and having novel operating mechanism 60 therefor.

These and other objects of this invention will appear as the following description thereof proceeds, and in order to more clearly understand said invention, reference may be had to the accompanying drawings which illustrate one embodiment of the inventive idea, and wherein—

Figs. 1 and 1^a are complementary side views of a folding machine equipped with sheet clamping, perforating, and registering mechanisms embodying the present invention;

Figs. 2, 3 and 4 are diagrammatic side views, partly in section, of the folding machine and said mechanisms, showing the positions occupied by the latter when the sheet is fed thereto, perforated, and folded, respectively;

Fig. 5 is an enlarged detail perspective view of the perforating mechanism and devices for operating the latter and the registering of gauge mechanism;

Fig. 6 is an enlarged detail perspective view of the gauge mechanism and operating devices therefor;

Fig. 7 is a side elevation, partly in section, of a clamp forming part of said gauge mechanism;

Fig. 8 is an enlarged detail perspective view of the perforating mechanism and part of the operating means therefor;

Fig. 9 is a side elevation, partly in section, of the perforating devices, illustrating the shear action obtained thereby on the sheet to perforate it;

Fig. 10 is a detail cross-sectional view, partly in side elevation, of the perforating mechanism and portions of the sheet feeding and folding mechanisms, the perforating mechanism being shown in its raised or upper position; and

Fig. 11 is a detail cross-sectional view of the perforating mechanism, the same being shown in its lower position.

Referring to the drawings, wherein like reference characters indicate like parts throughout the several views, 5 indicates generally the framework of a folding machine, said framework including supporting legs 6, 7, and side frame members 8 which are bolted or otherwise suitably secured to the framework 5. Mounted on the supporting legs 7 of the machine is an electric motor 9 supplied with current from any suitable source and controlled through a suitable switch (not shown) to start and stop said motor. The armature shaft 10 of the motor 9, has fixed thereon a pulley 11 around which passes a belt 12 that also passes around a pulley 13 which is fixed on a shaft 14 extending transversely of the machine and journaled in suitable bearings on the framework thereof.

Fixed on the shaft 14 is a pinion 15 which meshes with a large gear 16 that is fixed on a shaft 17 extending transversely of the machine 120

and journalled in suitable bearings on the machine framework. This shaft 17 has fixed thereon cams (not shown) which operate arms 18 and 19 that are pivoted in any suitable manner on the side frame members 8 and support drop rollers 20 and a folding blade 21, respectively. The sheet 22 is fed between the drop rollers 20 and conveyor tapes 23 which carry said sheet forwardly until its leading edge engages a stop 24, whereupon the folding blade 21 descends and folds the sheet between folding rollers 25, 26. The conveyor tapes 23 pass around a driving roller 27 and rollers 28, 29, 30, the roller 30 being journalled in arms 31 pivoted in any suitable manner on the machine framework 5 and carrying counterweights 32 for taking up the slack in said tapes. The roller 27 is driven in the usual or any well known manner and said roller, together with the rollers 28 and 29 are mounted on suitable shafts extending transversely of the machine and carried by the side frame members 8 thereof. The front stop 24 may be of the usual or any well known construction, and is mounted on a member 33 extending transversely of the machine and secured to the side frame members 8 thereof by any suitable means for this purpose (Figs. 2, 3 and 4).

The folding rollers 25, 26 are fixed on shafts 34 and 35, respectively, which extend transversely of the machine and are journalled in suitable bearings on the frame members 8 thereof. Fixed on the shaft 35 is a pinion 36 which meshes with the large gear 16 that is fixed on the shaft 17. The shaft 35 and the roller 26 are thus driven from the shaft 17 through the gear 16 and described connections therefor with the motor 9. Fixed on the end of the shaft 35 back of the gear 36 is a pinion 37 (Fig. 2) which meshes with a pinion 38 that is fixed on the shaft 34 and serves to drive the latter and the roller 25. Passing around the roller 26 and between the latter and the roller 25 are tapes 39 which extend in a substantially horizontal direction forwardly of the rollers 25, 26, and pass around idler rollers 40, 41 and 42. The idler rollers 40 and 41 are mounted on shafts extending transversely of the machine and mounted on the side frame members 8 thereof in any suitable manner. The idler roller 42 is carried by a shaft mounted in arms 43 pivoted in any suitable manner on the machine frame work 5 and carrying counterweights 44 for taking up the slack in the conveyor tapes 39.

The pinion 15 meshes with a pinion 45 that is fixed on a shaft 45' extending transversely of the machine and journalled on the side frame members 8 thereof. The shaft 45' has fixed thereon a gear 46 which meshes with a gear 47 that is journalled in any suitable manner on the machine framework. The gear 47 meshes with a pinion 48 that is fixed on a shaft 49 at one end thereof. The shaft 49 extends transversely of the machine and is journalled in suitable bearings on the side frame members 8 thereof. Fixed on the shaft 49 at the end thereof opposite that carrying the pinion 48 is a pinion 50 which meshes with a pinion 51 that is fixed on a shaft 52. This shaft 52 extends transversely of the machine and is journalled in suitable bearings on the frame members 8 thereof. Fixed on the shafts 49 and 52 are rollers 53 and 54, respectively, and said rollers, together with a folding blade 55 constitute a second folding mechanism receiving the sheet from the tapes 39 and acting to impart a second fold in said sheet par-

allel to the fold made therein by the first folding blade 21 and the rollers 25, 26. The blade 55 is mounted on arms 56 operated in the usual or any well known manner by cams and springs (not shown) to raise and lower said blade. 80 Passing around the folding roller 54 and between the latter and the folding roller 53 are conveyor tapes 57 which extend forwardly in a horizontal direction from the rollers 53 and 54 and pass around idler rollers 58 and 59. The idler rollers 58, 59 are carried on shafts adjustably supported in brackets 60 bolted or otherwise suitably secured to the framework 5 of the machine. 85

The above described folding mechanism operates to produce two parallel folds in sheet 22, but it is obvious that additional parallel folds as well as right angle folds, could be made in the sheet through the provision of additional folding devices constructed and operated substantially the same as those above described. If, for example, it should be desired to impart a third parallel fold to the sheet, the twice folded sheet would be conveyed by the tapes 57 to a sheet stop 61 adapted to register the sheets with respect to a right angle folding mechanism (not shown) for folding the sheet and delivering it from the machine. On the other hand, the twice folded sheet could be delivered directly from the machine by raising the stop 61 out of 100 the path of travel of the sheet on the tapes 57. 90

In accordance with the present invention, the sheet, after receiving one or more folds, is perforated on a line or fold by mechanism disposed at one side of the following folder, the sheet 110 thereafter being advanced by gauging and gripping mechanism to bring the perforated line or fold of the sheet in proper relation to said folder so that the sheet may be folded thereby. As herein shown, the perforating mechanism is 115 mounted between the first and second folding devices, and the gauge and grippers comprising said gauging mechanism are mounted forwardly of the second folding mechanism with the blades and folding rollers thereof interposed between 120 the perforating mechanism and the gauging mechanism. The perforating mechanism, in accordance with the present invention, has a shear action enabling the perforations to be more readily and accurately made in the sheet, and 125 the grippers of the gauge mechanism act to clamp the sheet during the perforating operation, and to thereafter draw the sheet forwardly into position for folding by the following folding mechanism. 130

The gear 48 meshes with a large gear 62 which is fixed on a stub shaft 62' journalled in a suitable bearing on one of the side frame members 8. The stub shaft 62' has fixed thereon a pinion 62'' which meshes with an idler gear 63 that is 135 journalled in any suitable manner on one of the side frame members 8 of the machine. This idler gear 63 meshes with a gear 64 that is fixed on one end of a shaft 65 extending transversely of the machine and journalled in suitable bearings provided by brackets 65' that are bolted or otherwise suitably secured to the frame members 8. The shaft 65 is thus driven through the described connections therefor with the motor 9 and constitutes a main cam shaft of the perforating and gauge mechanisms. Fixed on the shaft 65, in spaced relation, are cams 66, 67 having high and low portions 66', 66'' and 67', 67'', respectively. The cams 66, 67 are turned relatively to each other through a slight angle, and 140

are fixed on the shaft 65 so that the high portions 66', 67' of said cams successively engage rollers 68 on forks 69 that straddle the shaft 65. This angular setting of the cams 66, 67 enables a shearing action to be imparted to the perforating device through successive engagement of the cam portions 66', 67' with the rollers 68 of the forks 69 which operate said perforating device. The forks 69 are mounted on corresponding ends of rods 70, the opposite ends of which are pivotally connected at 71 with arms 72. The rods 70 are each preferably made in two parts adjustably connected together by turn buckles 73 that enable said rods to be lengthened or shortened, as desired. The arms 72 are fixed on stub shafts 74 journalled in suitable bearings in brackets 75 that are bolted or otherwise suitably secured to the side frame members 8 at points rearwardly of the second folding mechanism. The shafts 74 are thus rocked successively in the same direction by the described connections therefor with the cams 66, 67, said shafts being rocked in the opposite direction by spring pressed rods 76, the lower ends of which are guided by suitable means on the machine framework 5, and the upper ends of which are pivotally connected at 77 with arms 78 that are fixed on said shafts 74.

Rigidly secured to or formed integrally with the arms 72 are arms 79 provided longitudinally thereof with slots 80. The opposite walls of the slots 80 are grooved longitudinally thereof at 81 to receive and fit cylindrical members 82 fixed on or formed integrally with pins 83 that extend transversely of the members 82 and project from opposite sides of said members 82, as clearly shown in Fig. 8 of the drawings. The pins 83 are journaled in suitable bearings formed in brackets 84 that are bolted or otherwise suitably secured at 85 on the two parts 86, 86 of a perforator head indicated broadly at 87. The parts 86, 86 of the perforator head 87 are preferably formed of angle iron and have recesses 88 along the length thereof for the reception of perforating devices 89. These perforating devices are secured in position in said recesses by machine screws 90 or other suitable fastening devices which pass through aligned openings in the perforator head and the perforating devices and clamp the latter between the parts 86, 86 of said perforator head.

In assembling the perforator head and parts carried thereby, the perforating devices 89 are clamped between the parts 86, 86 of said head by the machine screws 90 or other fastening devices, whereupon the pins 83 are fitted in the bearings of the brackets 84 with the cylindrical members 82 each positioned between a pair of said brackets. The brackets 84 are then bolted to the parts 86, 86 of the perforator head and the latter is mounted on the arms 79 by sliding the cylindrical elements 82 through the open ends of said arms into engagement with the curved surfaces 81 on opposite walls of the slots 80. Thereafter, plates 91 are bolted or otherwise suitably secured, as at 92, 92, on the arms 79 to close the open ends thereof, strengthen the same, and prevent displacement of the perforator head from said arms during the operation of the machine.

Yieldably mounted on the perforator head 87 at opposite sides of the lower serrated edges 93 of the perforating devices 89, are clamping plates 94, the opposite ends of which have pins 95 secured thereto in any suitable manner. These

pins 95 extend through suitable openings in the enlarged, opposite ends 96 of the perforator head members 86, and secured on the upper ends of the pins 95 are heads 97 for preventing displacement of the clamps 94 from the perforator head 87. The clamps 94 have secured thereto pins 100 which project upwardly through suitable openings 98 in the parts 86 of the perforator head 87. Mounted on the pins 100 between the clamps 94 and the top of the perforator head 87, are springs 99, which normally tend to yieldably urge the clamps 94 and the head 87 apart.

The perforator head 87 is provided on the enlarged ends 96 thereof with outwardly projecting and vertically extending guides 101 which are received in guide slots 102 (Fig. 1) formed in the brackets 75 which are bolted or otherwise suitably secured to the side frame members 8. The slots 102 in the brackets 75 serve to guide the perforator head 87 vertically as said head is reciprocated by the cams 66, 67, the cam operated rods 70, and the spring pressed rods 76.

Extending transversely of the machine below, and in alignment with, the perforator head 87, is a perforator plate that is indicated broadly at 104. This perforator plate is made in two parts 105, 105', said parts being of general rectangular shape in cross-section, and the part 105 having slots 106 formed therein to receive the perforating devices 89 when the head 87 is lowered to perforate a sheet fed by the tapes 39 between the perforator head and the perforator plate. The part 105 of the perforator plate is secured in any suitable manner on brackets 107 bolted or otherwise suitably secured on a cross member 107'. The cross member 107 is secured by machine screws 109 or other suitable fastening devices to the side frame members 8 of the machine. The part 105' of the perforator plate is secured to the part 105 thereof, by machine screws or the like 110 (Figs. 10 and 11). When a sheet is fed by the tapes 39 between the perforator head and the perforator plate, said sheet is registered, by means hereinafter described, with the perforating devices 89 of said head, whereupon the cams 66, 67 operate to move the head 87 and the clamps 94 downwardly until the latter engage the sheet and clamp it on the perforator plate 104. The perforator head, however, continues to descend, and the cams 66, 67, operating one after another, impart a shearing action of the perforating device 89 to the sheet from one side thereof to the other. This shearing action is illustrated diagrammatically in Fig. 9 of the drawings, wherein it will be noted that the perforating device at the extreme right-hand end of the head has just engaged the sheet, at which time said sheet is clamped against the perforator plate 104 by the clamping plate 94. The head 87 continues to descend, the springs 99 yielding to provide for descent of the head and passage of the perforating devices 89 successively or progressively through and across the sheet and into the slots 106 of the perforator plate 104. The position of the parts when the sheet has been perforated, is shown in Fig. 11 and as soon as the perforating operation has been completed, the perforator head and parts carried thereby including the clamps 94, are raised by the spring operated rods 76 to the full line position shown in Fig. 10 of the drawings. When the perforator head 87 rises, the clamps 94 are lowered slightly

by the springs 99, thus insuring that the sheet will be stripped from the perforating devices 89. At this time, gauge mechanism which has previously registered the sheet with respect to the perforating devices and clamped the sheet while being perforated, moves the sheet over the second folding devices to a point where the line of perforation is disposed above the bite of the folding rollers 53, 54. This gauge mechanism and clamping means is preferably operated and constructed as follows:

Fixed on the cam shaft 65, at one end thereof, is a cam 111 which, during rotation of said cam shaft, engages a roller 112 that is journaled on an arm 113 having secured to or formed integrally therewith a fork 114 that straddles the cam shaft 65. The arm 113 is pivotally connected at 115 with an arm 116 of a lever 117. This lever 117 is pivoted at 118 on one of the side frame members 8 of the machine, said lever being provided on its upper end with an arcuate shaped rack 119. The lower end of the lever 117 is pivotally connected at 120 with one extremity of a spring pressed rod 121, the opposite extremity of which is guided in any suitable manner on the machine framework 5. The cam 111 and the spring pressed rod 121 thus serve to rock the lever 117 on its pivot 118 so that like motion is imparted to the rack 119. Meshing with the rack 119 is a pinion 122 that is fixed on a shaft 123 at one end thereof. This shaft 123 extends transversely of the machine and is journaled in suitable bearings in frame members 8 thereof. Fixed on the shaft 123, in spaced relation thereon, are pinions 124 which mesh with racks 125. When the arm 117 and the rack 119 are rocked by the described means for this purpose, the pinion 122, the shaft 123, and the pinions 124 are rotated first in one direction and then in the opposite direction, to reciprocate the racks 125 longitudinally of the machine. These racks 125 are guided, during their reciprocating movement, by guide blocks 126 on which said racks are slidably mounted. The guide blocks 126, in turn, are bolted or otherwise suitably secured to the side frame members 8 of the machine, and provide bearings for the shaft 123 and a shaft 127 (Fig. 6) extending in parallel relation therewith. This shaft 127 has fixed thereon a hand wheel 127' (Fig. 1) and worm pinions one of which is indicated at 128. These worm pinions serve to adjust a pair of gauge devices, one at each side of the machine, and since these gauge devices, and their adjusting and operating mechanisms, are identical in construction, it is only necessary to describe one of the same.

The worm pinion 128 meshes with a worm pinion 129, the worm pinion 129 being keyed on a shaft 130 and retained against endwise movement thereon by suitable means for this purpose. The shaft 130 is journaled in a bearing 131 formed on a bracket 132 that is bolted or otherwise suitably secured at 133 on the under-side of one of the racks 125. The bracket 132 and the bearing 131 provided thereby, are spaced at proper distances from the corresponding guide block 126 so as not to interfere with the reciprocating movement of the racks 125 thereon. The shaft 130 is retained against endwise displacement in the bearing 131 by a collar 134 which is secured to said shaft at opposite sides of said bearing. Each shaft 130 is provided with a threaded portion 135 that extends through and has threaded engagement with the

wall of a suitable opening formed in a bracket 136 that is bolted or otherwise suitably secured at 137 to a front stop 138. This front stop 138 extends transversely of the machine and may be adjusted longitudinally thereof for sheets of different sizes, by turning the shaft 127 to rotate the worm pinions 128, 129 and the shafts 130. When the shafts 130 are thus rotated, their threaded portions 135 act to move the front stop 138 forwardly or rearwardly in accordance with the direction of rotation of said shaft. It will appear, from the foregoing, that through the described operating connections for the front stop 138 with the cam shaft 65, the said front stop is reciprocated longitudinally of the machine toward and away from the sheet perforating mechanism above described. During reciprocating movement of the front stop 138 each shaft 130 slides in its worm pinion 129 which, for this purpose, is keyed at 139 in a slot 140 that extends longitudinally of the shaft 130. The sheet stop 138 moves toward and away from the perforating mechanism and also toward and away from the folding rollers 53, 54 of the second folding device, the sheet perforating mechanism being disposed at one side of said rollers, and the sheet stop 138 and parts carried thereby being disposed at the opposite sides of said rollers. Secured to the sheet stop 138 in any suitable manner and projecting from said sheet stop toward the folding rollers 53, 54, are sheet guides 141, 142 between which the sheet is fed by the tapes 39 into engagement with said sheet stop.

The sheet stop 138 also has secured thereto in adjustably spaced relation, two gauge and gripping mechanisms each comprising a stationary gripper jaw 143 and a movable gripper jaw 144. The gripper jaw 143 projects from said sheet stop toward the sheet perforating mechanism and the folding rollers 53, 54, the sheet being fed by the tapes 39 onto said jaw and between the sheet guides 141, 142 until the leading edge of the sheet engages the sheet stop 138. When the sheet stop 138 moves rearwardly and registers the sheet so that the second fold line thereof is directly below the perforating devices 89, the movable gripper jaw 144 clamps the sheet to the stationary gripper jaw 143 and thus prevents displacement of the sheet 125 while it is being perforated. Thereafter, the sheet stop 138 moves forwardly with the sheet clamped between the jaws 143, 144 until the perforated second fold line of the sheet is brought directly over the bite of the folding rollers 53, 54. The movable gripper jaws 144 are preferably operated and constructed as follows.

Fixed on the cam shaft 65 in spaced relation thereon, are cams 145 that engage rollers 146. These rollers 146 are journaled on forks 147 which straddle the cam shaft 65 and are secured on the forward ends of short rods 148. The rear ends of the rods 148 are pivotally connected at 149 with horizontally extending arms 150 that are fixed on the upper ends of vertical stub shafts 151. The stub shafts 151 are journaled in suitable bearings provided by brackets 152 that are bolted or otherwise suitably secured to brackets 153 (Fig. 1). These brackets 153, in turn, are bolted or otherwise suitably secured on the side frame members 8 of the machine. Fixed on the lower ends of the stub shafts 151 are arms 154 the free ends of which are provided with forks 155. The forks 155 en-

gage pins 156 that are secured to or formed integrally with the inwardly extending arms 157 of blocks 158. These blocks 158 have outwardly projecting guides 159 that are slidably mounted in guide ways 160 (Fig. 1) formed in the brackets 153 and extending in a direction transversely of the machine. Secured to the pins 156 are hooks 161 with which are engaged the inner ends of springs 162. The other ends 10 of the springs 162 are each secured to a pin 163 (Fig. 1) that, in turn, is secured to and projects upwardly from the cover 164 of the adjacent guide way 160.

Blocks 158 are moved inwardly toward each other by the arms 154 and the described connections therefor with the cams 145, said blocks being moved outwardly away from each other by the springs 162. The blocks 158 are thus cam operated in one direction and spring operated 20 in the opposite direction, the springs 162 maintaining the rollers 146 in engagement with cams 145 during rotation of the latter. The blocks 158, during their reciprocating movement inwardly and outwardly of the machine, 25 remain in substantial parallel relation with the side frame members 8 thereof so that grooves 158' formed in the blocks 158 and extending longitudinally thereof at right angles to the guides 159, are likewise retained in parallel relation. Each block 158 is utilized to operate the jaw 144 of one of the pairs of gauging and gripping mechanisms above referred to, and for this purpose, a slide bar 166 is associated with each jaw 144 and has a pin 165 which projects 30 upwardly into the groove 158' of one of the blocks 158. The slide bar 166 is mounted in guides 167 and retained therein by plates 168 that are bolted or otherwise suitably secured, as at 169 to said guides. The guides 167 in turn, are bolted or otherwise suitably secured, as at 170, to the sheet stop 138 and project forwardly therefrom, as clearly shown in Fig. 6 of the drawings. The slide bar 166 is thus reciprocated on the sheet stop 138 by the corresponding block 158 and the described connections for said block with said slide bar. During reciprocating movement of the sheet stop 138 longitudinally of the machine, the pin 165 of the slide bar 166 slides in the groove 158' of 45 the block 158, the construction being such as to produce reciprocating movement of each block 158 and its slide bar 166 laterally of the machine, while at the same time allowing each slide bar to move forwardly and rearwardly of the machine with the sheet stop 138.

The sheet stop 138 is provided with hook shaped slots and upwardly projecting arms. Extending in each hook shaped slot 171 under each upwardly projecting arm 172 is a pin 173 which is rigidly secured on an arm 174 of a bell crank 175. The bell crank 175 is journalled on a pin 176 that is secured at 177 in a suitable opening formed in the corresponding arm 172 of sheet stop 138. The arm 178 of bell crank 175 has secured to or formed integrally therewith the movable gripper 144, said gripper projecting rearwardly from said arm in parallel relation with the corresponding stationary gripper 143. Adjustably mounted on the pin 176 and secured thereto in any suitable manner, is an adjusting nut 179 for regulating the tension of a coil spring 180 that is mounted on said pin between said adjusting nut and the hub of the bell crank 175. The inner end of the spring 180 is secured to the bell crank 175 and the outer end of said spring

is secured to the adjusting nut 179. A similar bell crank and similar devices for operating it, are employed for the other movable gripper (not shown). When each slide bar 166 is moved inwardly of the machine by the corresponding block 158, the pin 173 of the corresponding bell crank 175 is engaged by said slide bar, thus rotating the bell crank 175 on its pin 176 and moving the gripper 144 carried by said bell crank away from the corresponding gripper 143. The spring 180 is thus tensioned, and when the slide bar 166 is moved outwardly of the machine, the gripper 144 is moved toward the gripper 143 by the spring 180.

The construction of the cams on the cam shaft 65 and the timing of the various parts operated by said cams, is such that when the sheet stop 138 is moved rearwardly of the machine, it stops the sheet where the line of the second fold of the sheet is disposed directly below the perforating devices 89, and at one side of the bite of the second folding rollers 53, 54. The blocks 158 are then each operated to move the corresponding slide bar 166 outwardly and swing the gripper 144 thereon downwardly so that the sheet 90 is clamped between said gripper and the corresponding stationary gripper 143 with the leading edge of the sheet engaging the sheet stop 138. The positions of the various parts after the sheet has been perforated and positioned for folding 95 by the second folding blade 55, are indicated in full lines in Fig. 2 of the drawings, wherein it will be noted that the perforating devices and the second folding blade 55 are raised above the sheet after the latter has been fed against the 100 sheet stop 138, perforated by the devices 89, and moved by the grippers 143, 144 to position for folding by blade 55. During the perforating operation the clamps 94 and perforating head 87, are lowered by the head operating mechanism 105 so that the sheet is clamped on plate 104, and the perforating devices 89, with a shearing motion, such as before described, perforate the sheet on a line of the second fold to be made 110 therein by the second folding device. The positions of the various parts when the sheet is being perforated, are shown in full lines in Fig. 3 of the drawings, wherein it will be noted that the perforating head is lowered, the folding blade 55 is raised, and the sheet is gripped by the 115 grippers 143, 144. After the sheet has been perforated, the sheet stop 138 moves forwardly of the machine, the grippers 143, 144 being engaged with the sheet and pulling it forwardly until the 120 line of perforation in the sheet is immediately 125 over the bite of the folding rollers 53, 54. At this time the sheet stop 138 is at the limit of its forward movement, and each slide bar 166 is moved inwardly by the corresponding block 158, to raise the gripper 144 carried by said bar and release the sheet from said gripper and the corresponding gripper 143. The folding blade 55 then descends and with the folding rollers 53, 54, acts to fold the sheet on the line of perforation made thereacross by the perforating mechanism. The positions of the parts during the operation of the second folding device, are indicated in full lines in Fig. 4 of the drawings wherein it will be noted that the perforator head 130 135 140 145 nism for further folding the sheet, as desired. The above described operations are repeated successively as the sheets are fed in like manner to the described instrumentalities for folding, perforating, and again folding the sheet on the line 5 of perforation, and further and more detailed description of the operation of the machine is therefore unnecessary in view of the foregoing.

While one embodiment of the present invention has been illustrated and described in detail, 10 it is to be expressly understood that said invention is not limited to said embodiment or otherwise than by the scope of the appended claims.

What I claim is:

1. In a folding machine, sheet folding means, 15 a sheet stop, rack and gear means for moving the sheet stop toward and away from the sheet folding means, sheet gripping devices carried by and movable with the sheet stop and having relatively movable parts between which the sheet 20 is fed when said stop is moved toward the sheet folding means, and means for moving said parts of the sheet gripping devices relatively, whereby they are opened to receive the sheet and thereafter closed to move it in position for folding by 25 said folding means when the stop is moved away from the same.

2. In a folding machine, sheet folding means, a sheet stop movable toward and away from the same, means for moving a sheet into position for 30 folding by said sheet folding means and comprising a sheet gripping member fixed on the sheet stop and a sheet gripping member pivoted thereon, a slide on the sheet stop and adapted to swing the pivoted gripping member in one direction, and means for swinging said pivoted 35 gripping member in the opposite direction.

3. In a folding machine, sheet folding means, a sheet stop movable toward and away from the same, means for moving a sheet into position 40 for folding by the sheet folding means and comprising a pair of sheet gripping members fixed and pivoted on the sheet stop respectively, means movable along the sheet stop to swing the pivoted sheet gripping member in one direction, and 45 spring means on the pivotal axis of said pivoted gripping member and adapted to swing it in the opposite direction.

4. In a folding machine, sheet folding means, a sheet stop movable toward and away from the 50 same, means for pulling a sheet into position for folding by the sheet folding means and comprising a pair of sheet gripping members fixed and pivoted on the sheet stop respectively, means for moving the pivoted sheet gripping 55 member toward and away from the other sheet gripping member and including a gripper operating device carried by and slidable along the sheet stop, and means for reciprocating said gripper operating device as the sheet stop and sheet gripping members are moved toward and 60 away from said sheet folding means.

5. In a folding machine, sheet folding means, a device movable toward and away from the same and having a slot and an arm thereabove, 65 means for moving a sheet into position for folding by said sheet folding means and including a gripper pivoted on said arm and having a pin projecting through said slot, and means for operating the gripper and including a member movable along said device to engage said pin and swing said gripper.

6. In a folding machine, sheet folding means, a member movable toward and away from the same, means for moving a sheet into position 70

for folding by said sheet folding means and including a gripper pivoted on and movable with the aforesaid member, means for operating the gripper and including an element slidably mounted on said member and carrying a pin, and means for reciprocating said element and comprising a slidable device having an elongated groove receiving said pin and providing for movement of the element with said member. 80

7. In a folding machine, sheet folding means, gripper carrying means movable toward and away from the same, a pair of sheet grippers fixed and pivoted on the gripper carrying means respectively and adapted to grip and move a sheet into position for folding by the sheet 85 folding means, a gripper operating device slidably mounted on the gripper carrying means and adapted to engage and swing the pivoted gripper thereon, and reciprocating means adapted to operate said device and providing for movement of the same with said gripper carrying means.

8. In a folding machine, sheet folding means, gripper carrying means movable toward and away from the same, a pair of grippers on the 90 gripper carrying means and adapted to grip and move a sheet into position for folding by said sheet folding means, gripper operating means carried by the gripper carrying means and including an element slidable therealong, slidable means movable transversely of the direction of movement of the gripper carrying means and connected with said element to reciprocate it thereon, and means for reciprocating said 95 slidable means.

9. In a folding machine, sheet folding means, gripper carrying means movable toward and away from the same, a pair of grippers on the gripper carrying means and adapted to grip and move a sheet into position for folding by said 100 sheet folding means, gripper operating means carried by the gripper carrying means and including an element slidable therealong, a block slidable transversely of the direction of movement of the gripper carrying means and connected with said element to reciprocate it thereon, and means for reciprocating said 105 block and comprising cam and spring operated rocking means connected therewith. 110

10. In a folding machine, sheet folding means, gripper carrying means movable toward and away from the same, a pair of grippers on the gripper carrying means and adapted to grip and move a sheet into position for folding by said sheet folding means, gripper operating 115 means carried by the gripper carrying means and including an element slidable therealong and provided at one extremity with a pin, slidable means movable transversely of the direction of movement of the gripper carrying means and having a groove receiving said pin and extending transversely of said element, and means for reciprocating said slidable means and comprising a stub shaft, a cam operated arm fixed on the stub shaft to rock it in one direction, and a spring operated arm loosely engaged with the slidably mounted means and fixed on said shaft to rock it in the opposite direction. 125

11. In a folding machine, sheet folding mechanism, means for temporarily stopping a sheet 130 travelling toward the sheet folding mechanism, means adapted to perforate the sheet with a shearing action thereon when said sheet is stopped by said first named means, and means for moving the perforated sheet from the per- 135 140 145 150

- forating means into position for folding by said sheet folding mechanism.
12. In a folding machine, sheet folding mechanism, means for feeding a sheet thereto, and sheet perforating means adapted to progressively perforate the sheet transversely of its direction of feed before said sheet has reached a position for folding by said folding mechanism. 80
13. In a folding machine, sheet folding means, sheet perforating means past which a sheet is fed to said sheet folding means, and means for operating said sheet perforating means adapted to produce a progressive perforating action thereof on said sheet transversely of its direction of feed. 85
14. In a folding machine, sheet folding mechanism, means having reciprocating motion and adapted to progressively perforate a sheet fed thereto, and means for moving the sheet from said first named means to bring the progressively formed line of perforations of said sheet into register with said sheet folding mechanism. 90
15. In a folding machine, sheet folding mechanism, means for perforating a sheet fed thereto and folded thereby, a movable head carrying the sheet perforating means, and means for moving said head adapted to impart shearing motion to the latter and said sheet perforating means. 100
16. In a folding machine, sheet folding mechanism, a movable head, sheet perforating devices secured to said head at intervals along the same and adapted to perforate a sheet fed to said sheet folding mechanism, and head operating mechanism adapted to reciprocate the head and the perforating devices and produce a shearing action of the latter on said sheet when perforating the same. 110
17. In a folding machine, sheet folding mechanism, a slidably mounted head past which a sheet is fed to be folded by the sheet folding mechanism, sheet perforating means carried by the head and adapted to perforate the sheet for folding by said sheet folding mechanism, rocking means, and means slidably and pivotally connecting the head with said rocking means to reciprocate said sheet perforating means. 115
18. In a folding machine, sheet folding mechanism, a slidably mounted head past which a sheet is fed to the sheet folding mechanism, sheet perforating means carried by and movable in opposite directions with the slidably mounted head, bell cranks pivotally mounted adjacent the opposite ends of the head, cylindrical members pivotally mounted on the head and slidably received in arms of said bell cranks, and means for rocking the bell cranks to reciprocate the head and said sheet perforating means. 125
19. In a folding machine, sheet folding mechanism, a slidably mounted head made in two parts and past which a sheet is fed to the sheet folding mechanism, sheet perforating means secured to the head between the parts thereof and adapted to perforate the sheet before it is fed in position for folding by said sheet folding mechanism, and means for reciprocating said head and said sheet perforating means. 130
20. In a folding machine, sheet folding mechanism, a movable head past which a sheet is fed to the sheet folding mechanism, sheet perforating means carried by the movable head
- and adapted to perforate the sheet before it is fed in position for folding by said sheet folding mechanism, cylindrical members pivotally mounted on the head, and head operating means having opposed arcuate shaped grooves slidably receiving said cylindrical members. 80
21. In a folding machine, sheet folding mechanism, a movable head past which a sheet is fed to the sheet folding mechanism, sheet perforating means carried by the movable head and adapted to perforate the sheet before it is fed in position for folding by said sheet folding mechanism, and means for operating the head and the sheet perforating means and comprising movable members having opposed arcuate shaped grooves and cylindrical members slidably received in said grooves and pivotally connected with said head, and means for retaining the cylindrical members in said grooves. 90
22. In apparatus of the character described, means to which material is fed and adapted to progressively perforate said material transversely of its direction of feed, and means for folding the material on the line of perforations progressively made therein by said first named means. 95
23. In apparatus of the character described, means for feeding material, and perforating means and folding means to which the material is fed by said first named means, said perforating means being adapted to progressively perforate the material transversely of its direction of feed and said folding means being adapted to fold said material on the line of perforation progressively formed therein. 105
24. In apparatus of the character described, means to which material is fed and adapted to progressively perforate said material transversely of its direction of feed, means spaced from the perforating means and adapted to fold the material on the line of perforations progressively made therein by said first named means, and means for moving the material from said perforating means to said folding means. 115
25. The method of folding material, which consists in feeding said material, progressively perforating said material transversely of its direction of feed, and folding the material on the line of perforations progressively formed therein. 120
26. The method of folding material, which consists in feeding the material, progressively perforating said material transversely of its direction of feed, further feeding the material, and folding said material on the line of perforations progressively formed therein. 125
27. The method of folding material, which consists in feeding said material, temporarily stopping the same, progressively perforating the material while it is stopped as aforesaid, and folding the material on the line of perforations progressively formed therein. 135
28. In apparatus of the character described, means for temporarily stopping a travelling sheet, means for progressively perforating the sheet while it is stopped as aforesaid, and means for thereafter folding the sheet on the line of perforations progressively formed therein by said perforating means. 140

JOHN PERRY.
